ABSTRACT OF THE DISCLOSURE

These methods improve the operation of a phenol extraction process having two parallel contacting zones of unequal capacities. The method for improving the efficiency of the process comprises connecting two contacting zones in series with the existing two contacting zones. The method for improving the capacity and the efficiency of the process comprises connecting two contacting zones in series with the existing two contacting zones and employing interstage cooling.

BACKGROUND OF THE INVENTION

Lubricating oil fractions can be obtained from a petroleum crude oil. Such fractions contain not only the desired high viscosity index hydrocarbons, isoparaffins and cyclic compounds with long paraffinic side chains, but also undesirable highly condensed cyclic compounds of low viscosity index, polycyclics with no or only short side chains, and heterocyclics which reduce the oil's stability. The undesirable constituents are selectively removed from the oil by means of solvent extraction processes. These solvent extraction processes include the furfural, phenol, Duo-Sol, Edeleanu, Chlorex, and nitrobenzene processes.

Fundamentally, all of the above-mentioned processes are similar. In each, the oil is contacted with a selective solvent that extracts the undesirable components and, subsequently, the solvent is separated from the extract and raffinate streams. The solvent causes the hydrocarbon stream to separate into two phases, a first phase consisting primarily of solvent in which are dissolved the extracted objectionable bodies, such as polycyclic aromatics, and a second phase consisting of the refined oil saturated with the solvent. The primary purpose of these processes is to improve the quality of the lubricating oil distillate being treated by selectively removing the undesirable components therefrom, thereby improving the viscosity index and ability to resist oxidation of the distillate. Such separation of lubricating oil hydrocarbons is entirely physical. The yields of such a process vary with the efficiency of the solvent and the efficiency of the process itself. Efficiency is defined as the barrels of refined oil obtained per barrel of solvent charged to the extractors. This is a suitable definition, since the quantity of solvent used in the process has a large effect on the economics of the process. The cost of solvent recovery is high. Yield is defined as the barrels of refined oil obtained per barrel of distillate charged to the extractors.

A suitable solvent extraction process for the treating of lubricating oil distillates is the process that employs phenol as the solvent. In such a process, countercurrent contactors may be connected in series and an increase in the number of countercurrent contacting stages reduces solvent requirement and improves the selectivity of the process.

One phenol extraction process that has been in commercial operation comprises two parallel contacting zones of unequal capacity. In this process, a lubricating oil frac-

tion is treated to improve its color, its ability to resist oxidation, and its viscosity index. The lubricating oil fraction is introduced into the two parallel contacting zones, a first contacting zone and a second contacting zone. A first phenol stream is introduced into the first contacting zone and is passed therethrough countercurrently to the lubricating oil fraction. A second phenol stream is introduced into the second contacting zone and is passed therethrough countercurrently to the lubricating oil fraction. A first raffinate effluent and a first extract effluent are withdrawn from the first contact-zone while a second raffinate effluent and a second extract effluent are withdrawn from the second contacting zone. The first raffinate effluent and the second raffinate effluent comprise the improved lubricating oil distillate and make up the usable product of this process.

Now there have been found a method for increasing the efficiency and a method for increasing the capacity and the efficiency of this phenol extraction process wherein the amount of solvent required per barrel of lubricating oil fraction charged is reduced and the yield of usable product is increased.

SUMMARY OF THE INVENTION

Briefly, in accordance with the present invention, there is a method for increasing the efficiency of a process for treating a lubricating oil distillate to improve the color, the ability to resist oxidation, and the viscosity index of the distillate. The process to which this method is applicable comprises introducing a first phenol stream into a first contacting zone, passing said first phenol stream through said first contacting zone countercurrently to a first distillate stream, introducing a second phenol stream into a second contacting zone, said first contacting zone and said second contacting zone being parallel and being of unequal capacities, passing said second phenol stream through said second contacting zone countercurrently to a second distillate stream, said first distillate stream and said second distillate stream being charged to said first contacting zone and said second contacting zone, respectively, withdrawing from said first contacting zone a first extract effluent and a first raffinate effluent, and withdrawing from said second contacting zone a second extract effluent and a second raffinate effluent. The method for increasing the capacity of this process comprises: Combining the first extract effluent and the second extract effluent and to form an intermediate-extract effluent; passing said intermediate-extract effluent into and through an intermediate-extract surge drum; withdrawing said intermediate-extract effluent from said intermediate-extract surge drum; dividing said intermediate-extract effluent into a first intermediate-extract stream and a second intermediate-extract stream; passing said first intermediate-extract stream into and through a third contacting zone; introducing into said third contacting zone a third distillate stream, said third distillate stream being passed through said third contacting zone countercurrently to said first intermediate-extract stream; withdrawing from said third contacting zone a first final-extract stream and a first intermediate-raffinate stream; passing said second intermediate-extract stream into and through a fourth contacting zone; introducing into said fourth contacting zone a fourth distillate stream, said fourth distillate stream being passed through said fourth contacting zone countercurrently to said second intermediate-extract stream; withdrawing from said fourth contacting zone a second final-extract stream and a second intermediate-raffinate stream; passing said second intermediate-raffinate stream into and through an intermediate-raffinate surge drum; withdrawing said second intermediate-raffinate stream from said intermediate-raffinate surge drum; dividing said second intermediate-

raffinate stream into a third intermediate-raffinate stream and a fourth intermediate-raffinate stream; combining said first intermediate-raffinate stream with said third intermediate-raffinate stream to form a fifth intermediate-raffinate stream; passing said fifth intermediate-raffinate stream into said first contacting zone, said fifth intermediate-raffinate stream being said first distillate stream that is introduced into said first contacting zone; withdrawing as a first final-raffinate stream from said first contacting zone said first raffinate effluent; passing said fourth intermediate-raffinate stream into and through said second contacting zone, said fourth intermediate-raffinate stream being said second distillate stream that is introduced into said second contacting zone; withdrawing as a second final-raffinate stream from said second contacting zone said second raffinate effluent.

In this method, the third contacting zone and the fourth contacting zone may be of equal capacities. The first intermediate-extract stream and the second intermediate-extract stream may be equal in volume. The first contacting zone may be a gravimetric extractor, and the second contacting zone may be a centrifugal extractor.

Also, in accordance with the present invention, there is a method for increasing the capacity and the efficiency of the process. This method comprises the above-defined method and, in addition, cools the intermediate-raffinate material that is to be introduced into the first contacting zone to a temperature that is about 10° F. to about 25° F. lower than the temperature of the first phenol stream being introduced into the first contacting zone. Therefore, the first intermediate-raffinate stream may be passed through a cooler to cool the fifth intermediate-raffinate stream to a temperature that is about 10° F. to 25° F. lower than the temperature of the first phenol stream being charged to the first contacting zone. As an alternative, the fifth intermediate-raffinate stream may be passed through the cooler.

DESCRIPTION OF THE DRAWINGS

Two figures are presented herewith to facilitate better understanding of the present invention. FIGURE 1 is a simplified schematic drawing of the process for treating lubricating oil distillates to which the present invention is applicable. Two parallel contacting zones are employed in this process.

FIGURE 2 is a simplified schematic representation of the same process depicted in FIGURE 1 after the method of the present invention is employed.

In these simplified drawings, auxiliary equipment such as pumps, valves, and the like, are not shown. Moreover, the solvent recovery equipment is not shown. Such items, their use and location are well known to those people having ordinary skill in the art. Therefore, they need not be represented in the drawings.

Since the efficiency of a phenol extraction process can be improved through an increase in the number of extraction stages that are used in the process, contacting zones may be added in series with existing contacting zones to provide a more efficient phenol extraction process.

If an existing process for treating lubricating oil fractions comprises two parallel contacting zones, into which separate streams of the lubricating oil fraction are introduced and from which separate streams of raffinate are withdrawn as improved lubricating oil distillates, the efficiency of this process can be improved by connecting an additional two contacting zones in series therewith. If the existing two contacting zones are of unequal capacity auxiliary equipment such as surge drums may be employed to handle the intermediate-raffinate and intermediate-extract streams associated therewith.

Typical lubricating oil fractions that may be treated in a process that is improved by the method of this invention are petroleum hydrocarbon fractions boiling within the range of about 600° F. to about 1,050° F. at atmospheric pressure. Such fractions possess a viscosity at 210° F. within the range of about 35 SUS to about 160 SUS.

Such hydrocarbon fractions may be either waxy or de-waxed.

The phenol stream may be relatively anhydrous; in such case, water may be added to the first contacting zone in the phenol extraction system, since water reduces the solvency of the phenol.

In the following examples, which demonstrate the advantageous of the present invention, a lube oil distillate having a viscosity of about 100 SUS at 210° F. was employed as the feedstock.

Example I

FIGURE 1 represents schematically an actual commercial phenol extraction process. In this particular process, the first contacting zone was an extraction tower and the second contacting zone was a centrifugal contactor. The first contacting zone 11 and the second contacting zone 12 were being operated in parallel. Distillate was introduced into zone 11 near its bottom by way of line 13. This distillate was maintained at a temperature of about 140° F. and was used at a flow rate of about 250 barrels per hour (b./h.). Phenol was introduced into zone 11 near its top by way of line 14. This phenol stream was maintained at a temperature of about 170° F. and was charged at a flow rate of about 450 b./h. Water was introduced into contacting zone 11 by way of line 15 at a flow rate of 31 b./h. Final raffinate was withdrawn from the top of zone 11 by way of line 16 at a flow rate of about 192 b./h., while extract was withdrawn from the bottom of zone 11 by way of line 17 at a flow rate of about 539 b./h.

Distillate was introduced also into zone 12 by way of line 18. The flow rate of this later distillate stream was about 168 b./h. Phenol was charged to zone 12 by way of line 19 at a flow rate of about 302 b./h. Final-raffinate was withdrawn from zone 12 by way of line 20 at a flow rate of about 123 b./h., while extract was withdrawn from zone 12 by way of line 21 at a flow rate of about 347 b./h.

The total charge of lubricating oil distillate to the above process system was about 418 b./h. The total amount of product (raffinate) after solvent removal withdrawn from this process scheme was about 282 b./h. The rate of the total amount of phenol charged was 752 b./h. Therefore, the solvent-to-oil-ratio was 1.8 and the yield, i.e., the ratio of raffinate produced to the hydrocarbons charged, was 67.5 volume percent. More-over, the efficiency of this process, as defined above, was about 37.5 percent.

Example II

An embodiment of the present invention was employed to improve the efficiency of this above process. The process employing this embodiment is represented schematically in FIGURE 2. The original process scheme, as presented and numbered in FIGURE 1, is presented on the right-hand side of FIGURE 2. The lines and equipment presented on the right-hand side of the dotted line represent the lines and equipment that are shown in FIGURE 1. Therefore, they have the same numbers that are presented in FIGURE 1. Of course, the quantities of materials and flow rates employed in this scheme are different than those of the corresponding materials and streams employed in the process depicted in FIGURE 1. The cooler 39, represented by the broken lines, was not employed in the process of this example and should, therefore, be ignored in the discussion of this example.

Phenol was charged to contacting zone 11 by way of line 14 while a small amount of water was charged by way of line 15. The flow rate of phenol, maintained at a temperature of about 174° F., was about 348 b./h. The flow rate of the water was about 24.6 b./h. Intermediate extract was withdrawn from zone 11 by way of line 17 at a flow rate of about 439 b./h. Phenol was also charged to contacting zone 12 by way of line 19 at a flow rate of about 252 b./h. and was maintained at a temperature at

about 174° F. Intermediate extract was withdrawn from contacting zone 12 by way of line 21 at a flow rate of about 291 b./h. The extract effluent in line 21 was combined with the extract effluent in line 17 and the combined extract effluent was passed through line 22 into intermediate-extract surge drum 23. This surge drum was necessary, since unequal flows of extract were obtained from the two contacting zones. Extract was withdrawn from intermediate-extract surge drum 23 by way of line 24. This extract stream was then split into two equal streams, one of which passed through line 25, while the other passed through line 26. The flow rate of the material in line 25 as well as in line 26, was about 365 b./h. The extract from line 25 was introduced into contacting zone 27, while that from line 26 was introduced into contacting zone 28.

Distillate was charged to contacting zone 27 by way of line 29. Intermediate raffinate was withdrawn from contacting zone 27 by way of line 30, while extract was withdrawn from contacting zone 27 by way of line 31. The distillate was maintained at a temperature of about 163° F. and was introduced into zone 27 at a flow rate of about 187 b./h. The flow rate of the intermediate raffinate being withdrawn through line 30 was about 204 b./h.

Distillate was also charged to contacting zone 28 by way of line 32. The distillate was maintained at a temperature of about 166° F. and was added at a flow rate of about 187 b./h. Extract was withdrawn from contacting zone 28 by way of line 33, while intermediate raffinate was withdrawn from contacting zone 28 by way of line 34. The flow rate of the intermediate-raffinate stream passing through line 34 was about 204 b./h.

The intermediate-raffinate stream passing through line 30 was introduced into the intermediate-raffinate surge drum 35. This surge drum was employed to eliminate problems which would arise because of the unequal capacities of the contacting zones 11 and 12. The intermediate-raffinate stream was withdrawn from surge drum 35 by way of line 36. This intermediate-raffinate stream was then divided into two smaller streams, one passing through line 37, while the other passed through line 38. The flow rate of material passing through line 37 was about 172 b./h. The flow rate of material passing through line 38 was about 32 b./h. The intermediate-raffinate stream in line 34 was passed through line 40 and then combined with the intermediate-raffinate stream in line 38. The combined intermediate-raffinate stream was passed through line 13 into contacting zone 11 at a flow rate of 236 b./h. Final raffinate was withdrawn from the top of contacting zone 11 by way of line 16 at a flow rate of about 137 b./h. The intermediate-raffinate stream passing through line 37 was passed through line 18 into contacting zone 12 at a flow rate of about 172 b./h. A final-raffinate stream was withdrawn from contacting zone 12 by way of line 20 at a flow rate of about 133 b./h. The total amount of product (raffinate) after solvent removal withdrawn from this process was about 270 b./h.

The quantities of materials employed in this example indicate that the yield of this process was about 72.2 volume percent. The ratio of solvent to oil was about 1.6. The efficiency of this process was 45 percent. Therefore, it is seen that the use of this embodiment of the present invention reduced the required solvent-to-oil ratio from 1.8 to 1.6 and increased the efficiency from 37.5 percent to 45 percent.

A preferred embodiment of the present invention to improve the capacity and the efficiency of the process of Example I may be represented schematically by FIGURE 2, if a cooler is placed in line 34 thereof to cool the first intermediate-raffinate stream passing therethrough. Therefore, cooler 39, which is represented by the broken lines, is employed in and is included in the process scheme of this preferred embodiment.

Phenol was charged to contacting zone 11 by way of

line 14 while a small amount of water was charged to contacting zone 11 by way of line 15. The flow rate of phenol, maintained at a temperature of about 170° F., was 417 b./h. The flow rate of the water was about 29 b./h. Intermediate extract was withdrawn from zone 11 by way of line 17 at a flow rate of about 503 b./h. Phenol was charged to contacting zone 12 by way of line 19 at a flow rate of about 320 b./h. and was maintained at a temperature of about 170° F. Intermediate extract was withdrawn from contacting zone 12 by way of line 21 at a flow rate of about 371 b./h. The extract effluent in line 21 was combined with the extract effluent in line 17 and the combined extract effluent was passed through line 22 into intermediate-extract surge drum 23. Extract was withdrawn from intermediate-extract surge drum 23 by way of line 24. This extract stream was then split into two equal streams, one of which passed through line 25 while the other passed through line 26. The flow rate of the material in line 25, as well as in line 26, was 437 b./h. The extract from line 25 and the extract from line 26 were introduced into contacting zones 27 and 28, respectively.

Distillate, maintained at a temperature of about 200° F., was charged to contacting zone 27 by way of line 29 at a flow rate of about 230 b./h. Intermediate raffinate was withdrawn from contacting zone 27 via line 30 at a flow rate of about 240 b./h. Extract was withdrawn from contacting zone 27 by way of line 31.

Distillate was also charged to contacting zone 28 by way of line 32. This distillate was maintained at a temperature of about 200° F. and was charged at a flow rate of about 230 b./h. Intermediate raffinate was withdrawn from contacting zone 28 by way of line 34 at a flow rate of about 240 b./h. Extract was withdrawn from contacting zone 28 by way of line 33.

The intermediate-raffinate stream passing through line 30 was introduced into and through intermediate-raffinate surge drum 35 and line 36. The intermediate raffinate was then split into two streams; one passed through line 37, while the other passed through line 38. The flow rate of the material in line 37 was 200 b./h. The flow rate of the material in line 38 was 40 b./h. The intermediate-raffinate stream in line 34 was passed through cooler 39 and line 40. The cooled intermediate-raffinate stream in line 40 was then combined with the intermediate-raffinate stream in line 38. The combined intermediate raffinate was passed through line 13 into contacting zone 11. The cooler 39 was operated to provide a temperature for the intermediate raffinate passing through line 40 that blended with the temperature of the material in line 38 to furnish a temperature of about 150° F. for the intermediate-raffinate material being passed through line 13 into contacting zone 11. Hence, this material being charged into contacting zone 11 had a temperature of about 20° F. lower than that of the phenol that was charged to contacting zone 11. This cooled intermediate-raffinate stream was passed through line 13 at a flow rate of about 280 b./h. Final raffinate stream was withdrawn from the top of contacting zone 11 by way of line 16 at a flow rate of about 332 b./h. (10 vol. percent phenol). The intermediate-raffinate stream passing through line 37 was passed through line 18 into contacting zone 12 at a flow rate of about 200 b./h. A final-raffinate stream was withdrawn from contacting zone 12 by way of line 20 at a flow rate of about 149 b./h. (10 vol. percent phenol). The total amount of product (raffinate), after solvent removal, withdrawn from this process was about 336 b./h.

It is to be understood that the cooler could have been used in line 13 to cool the combined intermediate-raffinate stream rather than to cool only the intermediate-raffinate stream passing through line 34.

The yield of this example was about 73 volume percent and the efficiency of this process scheme was about 45.6 percent. The ratio of solvent to oil was about 1.6. The original process scheme, as shown in FIGURE 1, treated

distillate at a flow rate of about 418 b./h. The process of this example treated distillate at a flow rate of about 460 b./h. Hence, the capacity of the process was increased. The use of the interstage cooling, coupled with the increased staging, resulted in both increased capacity and increased efficiency. The reduction of the temperature of the intermediate raffinate being charged to contacting zone 11 lowered the operating temperature of the contacting zone 11, thus reducing the solvency of the phenol and permitting more selective separation in the contacting zone 11.

It is to be understood that these examples and the accompanying drawings are being presented for the purpose of illustration only and are not intended to limit the scope of the invention.

What is claimed is:

1. A method for increasing the efficiency of a phenol extraction process wherein a lubricating oil distillate is treated to improve its color, ability to resist oxidation, and viscosity index and wherein said distillate is introduced into two parallel contacting zones having unequal capacities, a first contacting zone and a second contacting zone, a first distillate stream is introduced into said first contacting zone and second distillate stream is introduced into said second contacting zone, a first phenol stream is introduced into said first contacting zone and is passed through said first contacting zone countercurrently to said first distillate stream, a second phenol stream is introduced into said second contacting zone and is passed through said second contacting zone countercurrently to said second distillate stream, a first raffinate effluent and a first extract effluent are withdrawn from said first contacting zone, and a second effluent and a second extract effluent are withdrawn from said second contacting zone, which method comprises: combining said first extract effluent and said second extract effluent to form an intermediate-extract effluent; passing said intermediate-extract effluent into and through an intermediate-extract surge drum; withdrawing said intermediate-extract effluent from said intermediate-extract surge drum; dividing said intermediate-extract effluent into a first intermediate-extract stream and a second intermediate-extract stream; passing said first intermediate-extract stream into and through a third contacting zone; introducing into said third contacting zone a third distillate stream, said third distillate stream being passed through said third contacting zone countercurrently to said first intermediate-extract stream; withdrawing from said third contacting zone a first final-extract stream and a first intermediate-raffinate stream; passing said second intermediate-extract stream into and through a fourth contacting zone; introducing into said fourth contacting zone a fourth distillate stream, said fourth distillate stream being passed through said fourth contacting zone countercurrently to said second intermediate-extract stream; withdrawing from said fourth contacting zone a second final-extract stream and a second intermediate-raffinate stream; passing said second intermediate-raffinate stream from said intermediate-raffinate surge drum; dividing said second intermediate-raffinate stream into a third intermediate-raffinate stream and a fourth intermediate-raffinate stream; combining said first intermediate-raffinate stream with said third intermediate-raffinate stream to form a fifth intermediate-raffinate stream; passing said fifth intermediate-raffinate stream into said first contacting zone, said fifth intermediate-raffinate stream being said first distillate stream that is introduced into said first contacting zone; withdrawing as a first final-raffinate stream from said first contacting zone said first raffinate effluent; passing said fourth intermediate-raffinate stream into and through said second contacting zone, said fourth intermediate-raffinate stream being said second distillate stream that is introduced into said second contacting zone; withdrawing as a second

final-raffinate stream from said second contacting zone said second raffinate effluent.

2. The method of claim 1 wherein said first contacting zone is an extraction tower and said second contacting zone is a centrifugal extractor.

3. The method of claim 2 wherein said third contacting zone and said fourth contacting zone are of equal capacities.

4. The method of claim 3 wherein said third contacting zone and said fourth contacting zone are centrifugal extractors.

5. A method for increasing the capacity and the efficiency of a phenol extraction process wherein a lubricating oil distillate is treated to improve its color, ability to resist oxidation, and viscosity index and wherein said distillate is introduced into two parallel contacting zones having unequal capacities, a first contacting zone and a second contacting zone, a first distillate stream is introduced into said first contacting zone and second distillate stream is introduced into said second contacting zone, a first phenol stream is introduced into said first contacting zone and is passed through said first contacting zone countercurrently to said first distillate stream, a second phenol stream is introduced into said second contacting zone and is passed through said second contacting zone countercurrently to said second distillate stream, a first raffinate effluent and a first extract effluent are withdrawn from said first contacting zone, and a second raffinate effluent and a second extract effluent are withdrawn from said second contacting zone, which method comprises: combining said first extract effluent and said second extract effluent to form an intermediate-extract effluent; passing said intermediate-extract effluent into and through an intermediate-extract surge drum; withdrawing said intermediate-extract effluent from said intermediate-extract surge drum; dividing said intermediate-extract effluent into a first intermediate-extract stream and a second intermediate-extract stream; passing said first intermediate-extract stream into and through a third contacting zone; introducing into said third contacting zone a third distillate stream; said third distillate stream being passed through said third contacting zone countercurrently to said first intermediate-extract stream; withdrawing from said third contacting zone a first final-extract stream and a first intermediate-raffinate stream; passing said second intermediate-extract stream into and through a fourth contacting zone; introducing into said fourth contacting zone a fourth distillate stream, said fourth distillate stream being passed through said fourth contacting zone countercurrently to said second intermediate-extract stream; withdrawing from said fourth contacting zone a second final-extract stream and a second intermediate-raffinate stream; passing said second intermediate-raffinate stream into and through an intermediate-raffinate surge drum; withdrawing said second intermediate-raffinate stream from said intermediate-raffinate surge drum; dividing said second intermediate-raffinate stream into a third intermediate-raffinate stream and a fourth intermediate-raffinate stream; cooling said first intermediate-raffinate stream and subsequently combining said first intermediate-raffinate stream with said third intermediate-raffinate stream to form a fifth intermediate-raffinate stream that is about 10° F. to about 25° F. lower than the temperature of said first phenol stream being charged to said first contacting zone; passing said fifth intermediate-raffinate stream into said first contacting zone, said fifth intermediate-raffinate stream being said first distillate stream that is introduced into said first contacting zone; withdrawing as a first final-raffinate stream from said first contacting zone said first raffinate effluent; passing said fourth intermediate-raffinate stream into and through said second contacting zone, said fourth intermediate-raffinate stream being said second distillate stream that is introduced into said second contacting zone; withdrawing as a second final-raffinate

stream from said second contacting zone said second raffinate effluent.

6. The method of claim 5 wherein said first contacting zone is an extraction tower and said second contacting zone is a centrifugal extractor.

7. The method of claim 6 wherein said third contacting zone and said fourth contacting zone are of equal capacities.

8. The method of claim 7 wherein said third contacting zone and said fourth contacting zone are centrifugal extractors.

9. A method for increasing the capacity and the efficiency of a phenol extraction process wherein a lubricating oil distillate is treated to improve its color, ability to resist oxidation, and viscosity index and wherein said distillate is introduced into two parallel contacting zones having unequal capacities, a first contacting zone and a second contacting zone, a first distillate stream is introduced into said first contacting zone and second distillate stream is introduced into said second contacting zone, a first phenol stream is introduced into said first contacting zone and is passed through said first contacting zone countercurrently to said first distillate stream, a second phenol stream is introduced into said second contacting zone and is passed through said second contacting zone countercurrently to said second distillate stream, a first raffinate effluent and a first extract effluent are withdrawn from said first contacting zone, and a second raffinate effluent and a second extract effluent are withdrawn from said second contacting zone, which method comprises: combining said first extract effluent and said second extract effluent to form an intermediate-extract effluent; passing said intermediate-extract effluent into and through an intermediate-extract surge drum; withdrawing said intermediate-extract effluent from said intermediate-extract surge drum; dividing said intermediate-extract effluent into a first intermediate-extract stream and a second intermediate-extract stream; passing said first intermediate-extract stream into and through a third contacting zone; introducing into said third contacting zone a third distillate stream, said third distillate stream being passed through said third contacting zone countercurrently to said first intermediate-extract stream; withdrawing from said third contacting zone a first final-extract stream and a first intermediate-raffinate stream; passing said second intermediate-extract stream into and through a fourth contacting zone; introducing into said fourth contacting zone a fourth distillate stream, said fourth distillate stream being passed through said fourth con-

tacting zone countercurrently to said second intermediate-extract stream; withdrawing from said fourth contacting zone a second final-extract stream and a second intermediate-raffinate stream; passing said second intermediate-raffinate stream into and through an intermediate-raffinate surge drum; withdrawing said second intermediate-raffinate stream from said intermediate-raffinate surge drum; dividing said second intermediate-raffinate stream into a third intermediate-raffinate stream and a fourth intermediate-raffinate stream; combining said first intermediate-raffinate stream with said third intermediate-raffinate stream to form a fifth intermediate-raffinate stream; cooling said fifth intermediate-raffinate stream to a temperature that is about 10° F. to about 25° F. lower than the temperature of said first phenol stream being charged to said first contacting zone; passing said fifth intermediate-raffinate stream into said first contacting zone, said fifth intermediate-raffinate stream being said first distillate stream that is introduced into said first contacting zone; withdrawing as a first final-raffinate stream from said first contacting zone and said first raffinate effluent; passing said fourth intermediate-raffinate stream into and through said second contacting zone, said fourth intermediate-raffinate stream being said second distillate stream that is introduced into said second contacting zone; withdrawing as a second final-raffinate stream from said second contacting zone said raffinate effluent.

10. The method of claim 9 wherein said first contacting zone is an extraction tower and said second contacting zone is a centrifugal extractor.

11. The method of claim 10 wherein said third contacting zone and said fourth contacting zone are of equal capacities.

12. The method of claim 11 wherein said third contacting zone and said fourth contacting zone are centrifugal extractors.
